DUAL SUPPORT BRACKET FOR TRASH RECEPTACLES

Tacko D. Alissandratos, P.O. Box 606,
Tampa, Fla.

Filed Mar. 13, 1963, Ser. No. 73,954

Term of patent 14 years

(Cl. D58—17)

FIG. 1 is a side elevational view of a dual support bracket for trash receptacles, showing my new design;

FIG. 2 is a top plan view thereof;

FIG. 3 is a bottom plan view thereof; and

FIG. 4 is an end elevational view thereof.

The dominant feature of my bracket as shown in the above figures resides in the ornamental configuration of the central, entirely open joining, spaced wall portions, which provides oppositely and outwardly curved central portions and continuing opposed enlarged end portions.

I claim:

The ornamental design for a dual support bracket for trash receptacles, substantially as shown and described.
